(57) **CLAIM**

The ornamental design for an FM transmitter and power supply/charging assembly for MP3 player, as shown and described.

DESCRIPTION

FIG. 1 is a front elevation view of an FM transmitter and power supply/charging assembly for MP3 player showing my new design;

FIG. 2 is a left-hand side elevation view thereof;

FIG. 3 is a right-side elevational view thereof;

FIG. 4 is a rear elevation view thereof;

FIG. 5 is a bottom plan view thereof; and,

FIG. 6 is a top plan view thereof.

The broken lines depicted in FIGS. 1-6 form no part of the claimed design.
